UNITED STATES PATENT OFFICE.

CHARLES N. JUDSON, OF BROOKLYN, NEW YORK.

APPARATUS FOR CLOSING ELEVATOR-DOORS.

SPECIFICATION forming part of Letters Patent No. 476,388, dated June 7, 1892.

Application filed February 17, 1892. Serial No. 421,871. (No model.)

To all whom it may concern:

Be it known that I, CHARLES N. JUDSON, a citizen of the United States, residing at Brooklyn, in the county of Kings and State of New York, have invented a new and useful Improvement in Electrical Apparatus for Closing Elevator-Doors, of which the following is a specification.

It is well known that elevator shafts and cars are a great source of danger to the public from the fact that through the negligence or carelessness of the attendant or through faulty construction the doors or gates of such shafts or cars are either left open or are permitted to open accidentally—for instance, by the action of gravity while the elevator-car is in motion—and thereby persons are permitted to fall through the shaft and either killed or badly injured.

The object of my invention is to insure the closing of such doors or gates by means of an electric current operated, preferably, by the ordinary controlling device of the elevator-car, governing means for closing said doors without additional labor on the part of the attendant, or by means of an electric switch or the like operated from some local station either in the building or the car, by which said doors may be closed at the will of the attendant.

Figure 1 shows the application of my invention to the doors or gates of an elevator-shaft extending through two floors of a building, the doors at one floor (the first) being represented as open to allow passengers to enter or depart from the elevator-car, which is indicated in dotted lines at that floor, while the door at the floor above is represented as closed. Fig. 2 shows the application of my device to the door of the elevator-car itself.

In Fig. 1, D is an operating-pulley of the elevator, adapted to control the motor by which the car is elevated or lowered in the shaft.

C is the rope or controlling device by which the attendant controls the starting and stopping movement of the car.

B is an electric battery, preferably located in the basement of a building, with its circuit w running through the several electric motors which act to close the doors of the shaft and completing its circuit by means of the spring-

fingers d d, resting upon the pulley D, which rocks on its center in one direction or the other.

Upon the pulley D is placed an insulated surface I in such a way that when the fingers rest upon this insulated surface no current can pass through the wire w. When, however, the elevator-attendant operates the rope C, revolving the pulley D, for the purpose of causing the elevator-car to move, the spring-fingers are brought upon the connecting surface or contact K on the pulley D and the circuit is completed.

In Fig. 1 are shown the doors at two entrance-ways of the elevator-shaft, the elevator-car E C being indicated by the dotted lines behind the open door at the first floor, with the elevator-cable and attachment also shown in dotted lines, the car itself and its door-closing device being shown in detail in Fig. 2. Upon each door, preferably at the top, I place a rack R, whose teeth are adapted to engage with the teeth of the pinion Q, and these teeth in turn with the teeth upon the smaller pinion which is fixed upon the shaft P of an electric motor M. This motor is of the ordinary well-known kind, having a current movement in but one direction (shown by the arrows) and without any dead-point and when not under control of the current capable of being revolved backward by the movement of the rack upon the door. This motor is electrically connected with battery B by the main wire w, which includes each motor of the apparatus.

In the main circuit w is arranged a switch comprising the terminals or fingers d d and the pulley D, with its contact K and insulated surface I, the said fingers resting firmly against the pulley or disk D in an evident manner. This pulley D has an insulated surface I and a connecting-surface K so positioned upon the pulley D that when the pulley is turned sufficiently to set the car in motion the two spring-fingers d d shall rest upon the connecting-surface K and complete the circuit to the battery through the wire w.

Upon each door B' is placed an insulated circuit completing or connecting plate T, upon which rests one end of the spring-finger or contact t, the other end of said spring-finger being connected to the main circuit by the

branch wire w^2 . Near one side of the door is placed another spring-finger t' , so positioned that when the door B' is closed this spring-finger t' will rest upon the insulated connecting-surface upon the door. The other end of this spring-finger t' is also connected with the branch circuit w^2 , which joins the main circuit beyond the motor. For each motor there is also a second branch circuit w' , which is controlled by a switch S , by means of which the motor may be shunted. This switch is normally closed on the contact c in the main and is shifted to contact c' of the branch w' when the motor and its branch w^2 are to be cut out of the main circuit, which may be done when for any reason it is desired to throw a door and its motor out of the system.

The operation of my device may be described as follows: When the car is at rest—that is to say, not acted upon by the lifting device—the pulley D will be in a position shown in the drawings, with the two spring-fingers $d d$ resting upon the insulated portion I , so that no current is passing through the circuit w , the door B at the first floor being supposed to stand open for the admission of passengers. If now the attendant desires to start the car, the pulley D is turned by the controlling device C in the proper direction to cause the car to rise, and when both the spring-fingers $d d$ have come upon the connecting-surface K of the pulley D the circuit is completed from one terminal d through the main wire w and the motor back to the terminal d . If now the door of the shaft at the first floor be left open, the current causes the motor M to revolve and by means of the pinions P and Q and the rack R on the door causes the door B' to be moved until the latch catches upon the hasp and the door is held closed. Simultaneously with the closing of the door the spring-finger t' comes in contact with the electrical connecting-surface T , and the current then taking the course of the least resistance is shunted around the motor by way of the wire w^2 , spring-finger t , connecting-plate T , spring-finger t' , and wire w^2 back to the main circuit. The current then following the wire w to the motor adjacent to the door above in the shaft will, if that door be open, operate the motor and through the pinion and rack will cause the door to close, and upon the door being closed the current will be shunted, as before, through the wire w^2 , spring-finger t , connecting-surface T , spring-finger t' , and wire w back to the spring-fingers $d d$ to the battery. If at any time, for the sake of repairs and the like, it is desirable to keep any door of the shaft open while the elevator is being operated, the current is shifted by means of the switch S from the binding-post c to the binding-post c' , and the motor at that floor is then cut out from the circuit.

It will be understood that the motor M is so adjusted that when the current is cut out by the movement of the pulley D , so that

the spring-fingers $d d$ rest upon the insulated surface, the pinion in the motor is free to move backward, so that the door B' can be unlatched and pushed back by the attendant or pulled back by a counterbalancing-weight W^t , if desired.

In order to facilitate the opening of the door, I provide the same with a weight W^t , having a cord passing over a guide-pulley arranged at a convenient point. This weight will also serve to overcome the slight resistance which the idle motor imposes upon opening the door.

In Fig. 2 the operative parts of the door-closing device are the same, E C being the elevator-car, which is set in motion by an attendant through the controlling device C through the pulley D , the parts being in all respects the same as in Fig. 1, save that the main-circuit wire w is to be inclosed in the flexible tube J . In case there are two doors to the car, as is frequently the case where the openings or doorways in the elevator-shaft are upon different sides, the application and operation of my device will be the same as that applied to the shaft-doors; as is shown in Fig. 1, save that in the case of the car the two doors will be on different sides of the car, the current passing first through the motor of one door and then through the motor of another door and back to the pulley and battery, as in the case of the several shaft-doors.

In case it is desired that one door shall be cut out for the sake of repairs, &c., a switch identical with one shown in Fig. 1 is to be inserted in the line, so as to shunt the circuit around the first motor.

My invention is of broad scope, as will be seen from the claims, and various modifications of the same may be adopted without departing from the spirit of the invention.

It is evident that the controlling-switch of the main circuit may be arranged to operate independently of the controlling device C , and in this way the closing of all the doors of the series may be made certain by manipulating the switch; or, if preferred, an additional switch for controlling the main circuit may be used for hand operation. Any set of doors or gates or the like may be equipped with my invention, which is not necessarily limited to elevator-doors.

In the use of my invention the main circuit may obviously be controlled from any convenient point in any suitable manner instead of by the controlling device of the car. Such a circuit-controller or switch may be located, for instance, in the engineer's room. It may be located in the car itself, so as to be within convenient reach of the conductor or operator of the car, who may thus have control of the entire apparatus, the push-button or switch being an auxiliary attachment in such case, if preferred, or obviously it may take the place of the controlling device of the car in its function of controlling the main circuit. In Fig. 1 I have shown how this ar-

angement may be carried out, P B representing the push - button or circuit - controller, which is located within the car and connected with the terminals *dd* of the main circuit by means of the auxiliary lines *l*.

Though I have shown but one kind of controlling device C for the elevator-car, it is obvious that any character of such device may be used with the invention.

Having thus described my invention, what I claim, and desire to secure by Letters Patent, is—

1. The combination, with an elevator comprising a shaft and car, of one or more passenger - doors, electrically - operated mechanism connected with and positively actuating each door to close it, and a switch controlling said electrically - operated mechanisms, whereby any open door may be automatically closed by operating said switch.

2. The combination of a series of doors, an electric motor for closing each door, an electric circuit including said motors, and a switch controlling said circuit, whereby any open door of the series may be automatically closed by operating the switch.

3. The combination, with an elevator comprising a shaft and car and a controlling device for the car, of one or more doors, electrically - operated mechanism for closing each door, and a switch controlling said electrically - operated mechanisms, said switch connected with and operated by the said car-controlling device.

4. The combination, with an elevator comprising a shaft and car and a controlling device for the car, of one or more doors, an electric motor for closing each door, a source of electricity and an electric circuit leading therefrom and including said motors, means for automatically cutting each motor out of the circuit upon closing its door, and a switch controlling said circuit and connected with and operated by said car-controlling device.

5. The combination, with an elevator comprising a shaft and car, of one or more doors, an electric motor for closing each door, a source of electricity and a main circuit leading therefrom and including said motors, a branch circuit around each motor and circuit-completing mechanism located therein and operated by the door and serving to complete the circuit by way of the branch upon closing the door, whereby the motor thereof may be cut out of circuit, and a switch controlling the main circuit.

6. The combination, with an elevator comprising a shaft and car, of one or more doors, an electric motor for closing each door, a source of electricity and a main circuit leading therefrom and including the said motors, a branch circuit around each motor having circuit-completing mechanism located therein and operated by the door and serving to complete the circuit by way of the branch upon closing the door, whereby the motor thereof may be cut out of circuit, a normally-open

branch circuit for each motor provided with a hand - switch for shunting the motor and its branch at will, and a switch for controlling the main circuit.

7. The combination, with an elevator comprising a shaft and car and a controlling device for the car, of one or more doors, an electric motor for closing each door, a source of electricity and a main circuit leading therefrom and including said motors, a branch circuit around each motor provided with circuit-completing mechanism operated by the door and serving to complete the circuit by way of the branch upon closing said door, whereby the motor thereof may be cut out of circuit, and a switch controlling the main circuit and connected with and operated by said car-controlling device.

8. The combination, with an elevator-car and its door, of an electric motor for closing said door, a source of electricity and a circuit leading therefrom and including said motor, means for automatically cutting said motor out of circuit upon the closing of the door actuated thereby, and a switch for controlling said circuit.

9. The combination, with an elevator-car and its door, of an electric motor for closing said door, a source of electricity and a main circuit leading therefrom and including said motor, a branch circuit around said motor and circuit-completing mechanism located therein and operated by said door and serving upon closing the door to complete the circuit by way of the branch, thereby cutting the motor out of circuit, and a switch for controlling the main circuit.

10. The combination, with an elevator-car and its door and a controlling device for the car, of an electric motor for closing said door, a source of electricity and a main circuit leading therefrom and including said motor, means controlled by said door for cutting said motor out of circuit upon closing the door, and a switch controlling said main circuit and connected with and operated by said car-controlling device.

11. The combination, with a door having a rack for actuating it, of an electric motor geared to said rack, a branch circuit around the motor, and circuit-completing mechanism controlled by said door for completing the circuit by way of the branch upon closing the door, whereby the motor may be cut out of circuit.

12. The combination, with a door having a rack for actuating it, of an electric motor geared to the rack, a branch circuit around the motor and provided with contacts therein, and a circuit-completing plate mounted upon said door for making and breaking circuit with said contacts.

13. The combination, with an elevator comprising a shaft and car and a controlling device C for the car, of one or more doors and electrically - operated mechanism for closing each of said doors, a source of electricity and

a main circuit w , including said electrically-operated mechanisms, a switch located in the main circuit and comprising the terminals d and d , and a rocking switch-disk D , provided with 5 a contact K and operated by said car-controlling device C .

14. The combination, with an elevator comprising a shaft and car and a controlling device C for said car, of one or more doors B' , 10 an electric motor M for closing each door, a source of electricity and a main circuit w

leading therefrom and including said motors, a branch circuit w^2 around said motor and circuit-completing mechanism located therein and controlled by the door actuated by said 15 motor, and a switch located in the main circuit and connected with and operated by said car-controlling device C .
